(57) **CLAIM**

The ornamental design for watch case, as shown and described.

DESCRIPTION

FIG. 1 is an isometric view, from the front and above, of a watch case in accordance with the present invention.

FIG. 2 is a top plan view of the watch case of FIG. 1.

FIG. 3 is a front elevation of the watch case of FIG. 1.

FIG. 4 is a rear elevation of the watch case of FIG. 1.

FIG. 5 is a right side elevation of the watch case of FIG. 1.

FIG. 6 is a left side elevation of the watch case of FIG. 1; and,

FIG. 7 is a bottom plan view of the watch case of FIG. 1. The broken lines in the various figures show an environment which the invention may be associated and form no part of the claimed design.
